UNITED STATES PATENT OFFICE

139,326

DESIGN FOR A RECEPTACLE FOR TISSUE OR SIMILAR ARTICLE

Seymour E. Gordon, New York, N. Y.

Application July 17, 1944, Serial No. 114,426

Term of patent 7 years

(CL. D58—12)

To all whom it may concern:

Be it known that I, Seymour E. Gordon, a citizen of the United States, residing at New York, county of New York, and State of New York, have invented a new, original, and ornamental Design for a Receptacle for Tissue or Similar Article, of which the following is a specification, reference being had to the accompanying drawing, forming a part thereof.

Fig. 1 is a front perspective view of a recepta-

cle for tissue or similar article, showing my new design;

Fig. 2 is an end view thereof on a larger scale with a portion broken away for convenience of illustration.

I claim:

The ornamental design for a receptacle for tissue or similar article, as shown.

SEYMOUR E. GORDON.
